UNITED STATES PATENT OFFICE

95,410

DESIGN FOR A GLIDER FRAME

Harry H. Goldberg, Philadelphia, Pa.

Application January 14, 1935, Serial No. 54,850

Term of patent 3½ years

To all whom it may concern:

Be it known that I, Harry H. Goldberg, a citizen of the United States, and a resident of Philadelphia, county of Philadelphia, State of Pennsylvania, have invented a new, original, and ornamental Design for a Glider Frame, of which the following is a specification, reference being had to the accompanying drawing, forming a part thereof, wherein:

The figure is a perspective view of the glider frame, showing my design.

I claim:

The ornamental design for a glider frame as shown.

HARRY H. GOLDBERG.
